EXPLOSION-PROOF REFLECTOR ASSEMBLY
FOR PORTABLE ELECTRIC FLASHLIGHTSLeopold C. Grimsley, New York, N. Y., assignor
to Henry Hyman, New York, N. Y.

Application December 3, 1947, Serial No. 789,515

3 Claims. (Cl. 240—11.3)

1

This invention relates to explosion-proof reflector assemblies and, as shown herein, is particularly adapted to be incorporated in a portable electric flashlight of the type used in explosive atmospheres.

It is an object of the invention to provide a flashlight of the character described having an explosion-proof reflector assembly which comprises relatively few and simple parts and which is rapid and efficient in operation.

It is another object of the invention to provide an assembly of the type under consideration which is so constructed that it can be easily manipulated to insert a flashlight bulb and yet will positively lock the bulb in place.

Other objects of the invention will in part be obvious and in part hereinafter be pointed out.

The invention accordingly consists in the features of construction, combinations of elements and arrangement of parts which will be exemplified in the construction hereinafter described and of which the scope of application will be indicated in the appended claims.

In the accompanying drawings in which is shown one of the various possible embodiments of the invention,

Fig. 1 is a side view of a flashlight, the same being partially broken away in order to show the explosion-proof reflector assembly which incorporates the present invention;

Fig. 2 is a top plan view of said flashlight;

Fig. 3 is an enlarged sectional view through the flashlight, the same being taken substantially along the line 3—3 of Fig. 1; and

Fig. 4 is a sectional view taken substantially along the line 4—4 of Fig. 3, and showing the change in position experienced by the parts of the explosion-proof reflector assembly when the envelope of the lamp bulb breaks.

Referring now in detail to the drawings, the reference numeral 10 denotes a flashlight which is conventional in all respects save for the explosion-proof reflector assembly 12. Said flashlight comprises a molded casing 14 of synthetic resin, such, for instance, as ethyl cellulose. The casing is open at both ends and is adapted to house flashlight batteries 16. The lower end of the casing is provided with a male thread 17 on which an internally tapped bottom cap 18 is screwed. The joint between the bottom cap and casing is sealed by a rubber gasket 19. Said cap is provided with an annular shoulder 20 to seat a tapered helical battery compression spring 22. The lower end of the spring has an inturned leg 24 which engages a metal ferrule 26 riveted to the casing at the

lower end thereof. Said ferrule is in contact with a metal strip 28 running longitudinally of casing 14 and lying against the interior surface thereof. The strip 28 is connected by a rivet 30 to a conventional manually-operable flashlight switch 32 disposed on the exterior of the casing. This switch controls energization of another metal strip 34 which runs from said switch towards the upper end of the casing and terminates in a resilient finger 36. Attention is called to the fact that the switch is rendered gas and water-tight by a rubber diaphragm 37 interposed between the hand-operated parts and the current handling elements.

15 Said upper end of the flashlight casing is formed with a male thread 38 in order to have screwed thereon a lens cap 40. Said cap clamps a transparent plastic disc 42 against the upper rim of the casing. Rubber washers 44, 46 are interposed between the lens cap and plastic disc and between the plastic disc and upper rim of the flashlight casing to seal the upper end of the flashlight. Thus, the interior of the flashlight is isolated from the ambient air.

20 25 The lens cap also holds in a place a metal reflector 48 having an upper flange 50 caught between the lower washer 46 and upper rim of the flashlight casing. The center of the reflector is formed with a shallow recess 52 large enough to accommodate the flange 54 of a lamp 56 of the push or pre-focus type having a glass envelope 58. The bottom wall of said recess constitutes an in-turned ledge 60 to which a metal screw shell 62 is connected by a spun-over flange 64. The lamp flange 54 which is seated in the recess 52 comprises the side lamp contact and the same is connected to the cup terminal of the lowermost 30 35 battery through the reflector 48, resilient finger 36, switch 32 and battery compression spring 22.

40 45 The other leg of the electrical circuit to the batteries is completed with the aid of a cup-shaped bushing 66 of insulating material such as a synthetic resin. The interior of the bushing is provided with a threaded portion which is adapted to be screwed on the threaded portion of the screw shell 62 so as to pull the flange 64 against the ledge 60. A rivet 68 passes through the bottom wall of the bushing, the same being employed to hold a disc 70 to the outer surface 50 55 of the bottom wall and a disc 72 to the inner surface of the bottom wall. The lower end of said rivet lies over and abuts the central terminal of the uppermost battery. The disc 72 is disposed at the bottom of an upwardly converging central well 74 integrally formed within the base of the

bushing. Said well contains an upwardly tapering light helical compression spring 76, the diameter of whose lowermost convolution is less than the mouth of the well so that said spring is captively held within the well. The bottom of the spring is seated on the disc 72 and, during normal operation of the flashlight when the lamp flange 54 rests on the screw shell flange 64, the bottom terminal 78 of the lamp is in contact with the top of said spring, thus establishing an electric circuit from the central terminal of the uppermost battery to the bottom contact of the lamp. It may be mentioned that although the circuit just described provides a shock proof mounting for the lamp which protects the lamp from impact upon dropping the batteries into the casing, this type of mounting is not essential to the practice of the invention, and in lieu thereof, the bottom lamp terminal merely may abut against the central terminal of the uppermost battery. Said shock proof mounting is shown, described and claimed in my copending application Serial No. 789,514 filed December 3, 1947.

Means also is provided to strongly and continuously bias the lamp upwardly away from its operative position shown in Fig. 3, wherein the lamp flange 54 is seated in the recess 52 and contacts the screw shell flange 64. Said means consists of a relatively strong helical compression spring 80 whose lower end rests on the base wall of the bushing 66 and encircles the well 74. The upper end of the spring 80 is of a reduced diameter less than that of the lamp shell 62. The spring is of such length that when the lamp is in its operative position said spring is under compression. Thus, if no restraint is exercised to hold the lamp seated in the recess 52, the spring 80 will force the lamp away from the screw shell. Moreover, the spring is so long that when the lamp is not restrained said spring will force it so far away from the screw shell and from the reflector that the leg of the electric circuit to the lamp bulb through the reflector automatically will be broken.

Means is included to press the envelope of the lamp downwardly and thereby seat the lamp flange 54 on the screw shell against the action of the spring 80. Pursuant to the present invention, this means is so constructed that it comprises very few and simple parts so arranged that they may be manipulated with ease when a new lamp is inserted or a defective one removed. Said means comprises a yoke 84 of elongated slender stock, such, for instance, as wire, the material of the stock being self-form-maintaining and preferably somewhat resilient. By way of example, the wire of the yoke may be fabricated from steel. The yoke includes a base 86 and two downwardly depending parallel legs 88, 90. The center 92 of the base is in the form of a return bend or U as best seen in Fig. 2. The bottom ends of the legs terminate in registered out-turned toes 94.

The yoke is pivotally mounted on a hinge piece 96 which, in turn, is pivotally secured to a ring 98 forced up on the bushing against a shoulder 100. Said hinge piece comprises a curved strip 104 which can be swung on the ring to lie snugly against a side of the bushing adjacent the base thereof. Integrally attached to the strip are a pair of upstanding arms 108 which terminate in registered journals 110 whose apertures pivotally receive rivet-like projections 112 upset from the ring 98. The tips of the projections extend through the journal openings and are spun over to captively hold the hinge and ring together.

The strip 104 also has integrally formed therewith a pair of outwardly offset ears 114 having apertures 116 in which the toes 94 of the yoke are rotatably received.

5 The journals 110 and projections 112 are disposed on diametrically opposite sides of the bushing 66 so that the hinge 96 turns about an axis which is perpendicular to and intersects the axis of symmetry of the bushing 66. Said hinge 10 can swing about the projections 112 from a position in which the hinge is flat against the bushing, as shown in solid lines in Fig. 1, to an upward and outward position, for example, that shown in dot-and-dash lines in the same figure. The 15 apertures 116 (the axis of relative rotation between the yoke and hinge) are so disposed with respect to the projections 112 (the axis of relative rotation between the hinge and ring) and the lamp that when the hinge is in operative position with the strip 104 in contact with the bushing 66, and the base of the yoke pressing against the lamp envelope so as to seat the lamp in the recess 52, the legs of the yoke are on the opposite side of the axis of rotation of the hinge with respect to the ring from that on which said legs are disposed when the hinge is in its idle (dot-and-dash) position. This relative arrangement is best shown in Fig. 1. Preferably, said arrangement is such that when in their above-described operative position, the yoke legs are only slightly to one side of the pivotal axis connecting the hinge and ring so that when the hinge is moved but a short distance away from the bushing 66, said legs will be shifted to the opposite 35 side of the mentioned pivotal axis.

Means such as over-sized apertures 118 in the reflector 48 are provided to pass the legs of the yoke and constrain the yoke for slidable and pivotal movement relative to the reflector. Said 40 means performs several functions. Thus, it permits the yoke to extend from the envelope to the hinge; it definitely locates the operative position of the yoke; and it swings the base of the yoke out of the way to one side when the hinge is 45 shifted to idle position.

To mount a lamp 56 in the reflector assembly, the hinge member 96 is swung to its outermost idle position shown in dot-and-dash lines in Fig. 1. In this position the yoke is on the left of the 50 axis of pivotal connection between the hinge and ring. Since the yoke pivots about the apertures 118, the base 86 of the yoke will swing up and to the right of the lamp as seen in Figs. 1 and 2. Such movement is substantial and so disposes 55 the base of the yoke that it will not interfere with the seating of a lamp in the reflector. After the lamp is placed properly, the hinge is swung to its full line position indicated in Fig. 1. This will cause the return bend 92 to press against the 60 top of the glass envelope of the lamp with the projecting tip 120 of the lamp received within said bend. The yoke is so proportioned that in such position it will hold the lamp against its seat, overcoming the action of the compression 65 spring 80. The bulb is urged outwardly away from the reflector by said spring but this action does not tend to move the hinge to idle position inasmuch as, although the base of the yoke is pushed upwardly by the spring, the legs of the 70 yoke are so disposed with respect to the axis of pivotal connection between the hinge member and ring that the spring pressure urges the hinge to its operative position.

Because shifting the hinge between idle and 75 operative positions involves swinging the legs of

the yoke across the pivotal axis connecting the hinge and ring, said legs must elongate at the time of crossing. Such lengthening is taken care of by making the yoke resilient, as already noted, so that the base 86 can yield somewhat at the critical moments.

It may be observed that swinging the hinge into operative position will positively seat the lamp but will not always dispose the bottom of the return bend 92 against the tip of the lamp. 10 This exact positioning of the yoke may be accomplished by pressing the yoke manually after the hinge has been closed. Such additional movement of the yoke is permitted by the oversized openings 118.

If the envelope of the lamp should break, the base of the yoke no longer will exert any restraint upon the lamp so that the compressed spring 80 will force the base of the lamp upwardly to such an extent that contact is broken between the 20 spring 16 and the central terminal of the lamp, and between the lamp flange 54 and shell 62 or reflector. This latter position is illustrated in Fig. 4.

It thus will be seen that there is provided an explosion-proof reflector assembly which achieves the several objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, there is claimed as new and desired to be secured by Letters Patent:

1. The combination with a flashlight reflector assembly comprising a reflector having a large central opening through which the base of an electric lamp is adapted to pass, said lamp being of the push insertion type and having a central contact and a side contact in its base, means associated with the reflector for making electrical connection with the lamp contacts when the lamp is seated in the central opening, and means to bias the lamp in a direction out of said opening, said means when effective opening the electrical connections with the lamp contacts: of means to press against the envelope of the lamp so as to seat the same in the reflector against movement by said biasing means as long as the envelope is unbroken, said pressing means comprising a bushing, means to secure said bushing to said reflector beneath the lamp, a yoke including a base and a pair of spaced legs extending from the base in the same direction, a hinge member, means to pivotally secure said hinge member to said bushing for rotation about an axis perpendicular to the axis of symmetry of the reflector and on the same side of the envelope as the lamp base, and means to pivotally attach the legs of the yoke to the hinge member for rotation about an axis parallel to said first-named axis, said hinge member being swingable about the first-named axis from a position in which it rests against said bushing to a position in which it is spaced therefrom, said yoke member in the first-named position of the hinge member having its base pressing the envelope of the lamp against the biasing means so as to seat the lamp in the reflector and having its legs disposed on one side of the first-named axis, and said yoke member in the second-named position of the hinge member having its legs dis-

posed on the other side of said first-named axis, said reflector having openings therein through which the legs of the yoke pass.

2. The combination with a flashlight reflector assembly comprising a reflector having a large central opening through which the base of an electric lamp is adapted to pass, said lamp being of the push insertion type and having a central contact and a side contact in its base, means associated with the reflector for making electrical connection with the lamp contacts when the lamp is seated in the central opening, and means to bias the lamp in a direction out of said opening, said means when effective opening the electrical connections with the lamp contacts: of means to press against the envelope of the lamp so as to seat the same in the reflector against movement by said biasing means as long as the envelope is unbroken, said pressing means comprising a bushing secured to the reflector below the lamp, a ring carried by the bushing, a yoke including a base and a pair of spaced legs extending from the base in the same direction, a hinge member, means to pivotally secure said member to said ring for rotation with respect to the reflector about an axis perpendicular to the axis of symmetry of the reflector and on the same side of the envelope as the lamp base, means to pivotally attach the legs of the yoke to the hinge member for rotation about an axis parallel to said first-named axis, said hinge member being swingable about said first-named axis from a position in which it abuts said bushing to a position in which it is spaced therefrom, said yoke member in the first-named position of the hinge member having its base pressing the envelope of the lamp against the biasing means so as to seat the lamp in the reflector and having its legs disposed on one side of the first-named axis, and said yoke member in the second-named position of the hinge member having its legs disposed on the other side of said first-named axis, said reflector having openings therein to receive the legs of the yoke.

3. The combination with a flashlight reflector assembly comprising a reflector having a large central opening through which the base of an electric lamp is adapted to pass, said lamp being of the push insertion type and having a central contact and a side contact in its base, means associated with the reflector for making electrical connection with the lamp contacts when the lamp is seated in the central opening, and means to bias the lamp in a direction out of said opening, said means when effective opening the electrical connections with the lamp contacts: of means to press against the envelope of the lamp so as to seat the same in the reflector against movement by said biasing means as long as the envelope is unbroken, said pressing means comprising a bushing, a yoke including a base and a pair of spaced legs extending from the base in the same direction, a hinge member, means to pivotally secure said hinge member to said bushing for rotation about an axis perpendicular to the axis of symmetry of the reflector and on the same side of the envelope as the lamp base, and means to pivotally attach the legs of the yoke to the hinge member for rotation about an axis parallel to said first-named axis, said hinge member being swingable about the first-named axis from a position in which it rests against said bushing to a position in which it is spaced therefrom, said yoke member in the first-named position of the hinge member having its base pressing the envelope of the lamp against the biasing means so as to seat the lamp in the reflector and having its legs disposed on one side of the first-named axis, and said yoke member in the second-named position of the hinge member having its base pressing the envelope of the lamp against the biasing means so as to seat the

lamp in the reflector and having its legs disposed on one side of the first-named axis, and said yoke member in the second-named position of the hinge member having its legs disposed on the other side of said first-named axis, said reflector having openings therein through which the legs of the yoke pass.
